195,450

SODA FOUNTAIN OR SIMILAR ARTICLE

Herbert L. Smith, Van Nuys, Calif., assignor, by mesne assignments, to Phillips International, Inc., Los Angeles, Calif.

Filed Jan. 30, 1962, Ser. No. 68,580

Term of patent 7 years

(Cl. D2—3)

FIG. 1 is a perspective view of a soda fountain or similar article showing my new design;

FIG. 2 is a top plan view;

FIG. 3 is a front elevational view;

FIG. 4 is a side elevational view showing the right side thereof; and

FIG. 5 is a bottom plan view.

The rear is flat and substantially plain, as indicated by FIGS. 2, 4, and 5.

I claim:

The ornamental design for a soda fountain or similar article, substantially as shown and described.
